United States Patent Office

Des. 204,008
Patented Mar. 8, 1966

204,008

SHOVEL HANDLE

Leonard Louik, 7138 Reynolds St., Pittsburgh, Pa.

Filed Oct. 8, 1964, Ser. No. 82,082

Term of patent 14 years

(Cl. D39—1)

Fig. 1.

Fig. 2.

Fig. 3.

Fig. 4.

Fig. 5.

FIGURE 1 is a front elevational view of the shovel handle of my new design;

FIGURE 2 is a side elevational view thereof;

FIGURE 3 is a top plan view thereof;

FIGURE 4 is a bottom plan view thereof; and

FIGURE 5 is a perspective view thereof showing the front and side thereof opposite to those shown in FIGURES 1 and 2, respectively.

I claim:

The ornamental design for a shovel handle, as shown.
